UNITED STATES PATENT OFFICE.

RICHARD SCHEID, OF ST. LOUIS, MISSOURI.

MUFFLER CUT-OUT.

1,424,776.

Specification of Letters Patent. Patented Aug. 8, 1922.

Application filed April 1, 1921. Serial No. 457,748.

To all whom it may concern:

Be it known that I, RICHARD SCHEID, a citizen of the United States, residing at St. Louis, Missouri, have invented a certain new

5 and useful Improvement in Muffler Cut-Outs, of which the following is a full, clear, and exact description, such as will enable others skilled in the art to which it appertains to make and use the same, reference 10 being had to the accompanying drawings, forming part of this specification.

This invention relates to muffler cut-outs, the objects of the invention being to provide a muffler cut-out which is made of a one-piece casting and can be secured in position 15 on the exhaust pipe without having bolts or screws seated in said casting and engaging the exhaust pipe.

Another object of the invention is to provide 20 a valve for operation within said casting and having its actuating mechanism mounted on the exterior of said casting so that the mechanism is not subjected to the high temperature produced in the casting 25 by the exhaust gases and consequently is not effected or distorted by said high temperature.

Further objects of the invention are to provide 30 a housing on the underside of said valve in which is mounted the free end of the operating arm in such a manner that said valve will align itself with its seat and effectually close the discharge opening, and to provide improved means whereby said 35 casting will be securely held in position on the exhaust pipe without employing screws or like fastening devices on said casting or on said exhaust pipe.

With the foregoing and other objects in 40 view, my invention consists in certain novel features of construction and arrangement of parts, hereinafter more fully described and claimed, and illustrated in the accompanying drawings, in which—

45 Figure 1 is a front elevation partly in section with my improved muffler cut-out in position on the exhaust pipe of an engine.

Figure 2 is a horizontal section taken on line 2—2 of Figure 1.

50 Figure 3 is a vertical cross section taken on line 3—3 of Figure 1.

Figure 4 is an end elevation of a split ring used to secure the muffler in position.

55 Figure 5 is a detail view on the line 5—5 of Figure 1.

Figure 6 is a detail view of the clamping

ring showing a modified form of the slotted lugs, whereby the slot can be closed to retain said ring in engagement with the casting.

60

Referring by numerals to the accompanying drawings, which illustrate a practical embodiment of my invention, 10 designates the engine portion of the exhaust pipe and 11 the muffler portion thereof. The ends of these portions 10 and 11 are seated in the ends of a tubular casting 12 which is provided with an enlarged middle portion 14 having a chamber 15. In the underside of this middle portion 14 is arranged a circular opening 16 which is surrounded by an inwardly and upwardly extending annular flange 17. Opening 16 connects chamber 15 with the atmosphere and is normally closed by a circular valve 18 seated on flange 17. 70 The marginal flange 18^a of valve 18 is curved downwardly and extends below the edge of the upwardly presented flange 17.

75

The tubular ends of casting 12 are provided with inwardly projecting annular 80 flanges 12^a which form seats for the ends of exhaust pipe 11 and space said exhaust pipe from casting 12, thereby forming annular chambers 12^b which are adapted to be filled with a suitable packing 19 to form an air-tight joint between casting 12 and pipes 10 and 11. One of the annular flanges 12^a is extended inwardly into chamber 14 to form a seat 14^a and projecting inwardly from the extended portion of said flange 12^a is a lug 90 20 which limits the inward movement of pipe 11.

85

Projecting outwardly from the underside of valve 18 is a boxshaped housing 21, the rear portion of which is open. Extending 95 into this housing through said rear portion is the free end of a curved arm 22, which arm is fixed to a shaft 24 transversely journaled in lugs 25 projecting downwardly from the rear end of casting 12. A coiled spring 26 having one end anchored in one of the lugs 25 and its other end secured to arm 22 is positioned on shaft 24 and tends to hold valve 18 seated on flange 17 and thereby close discharge opening 16. Fixed 100 to one end of shaft 24 is an arm 27 which is adapted to be operated by the driver in any suitable manner.

105

Extending transversely through the housing 21 is a pin 29, the ends of which are 110 fixed in the side walls of said housing. This pin passes through the outer or free end of

lever 22 which is provided with an opening 22^a, the walls of which taper inwardly to form knife-edged seat for pin 29. Convex side faces 22^b formed on the free end of lever 22 bear against the side walls of housing 21 and permit rocking movement of valve 18 with respect to arm 22.

Means for fastening casting 12 in position on pipes 10 and 11 comprises split rings 30 having an outwardly projecting annular flange 31 which is adapted to be positioned against the end of casting 12 and close the annular spaces 12^b. Projecting inwardly from each flange 31 is a pair of longitudinal diametrically disposed lugs 32 provided with open slots 34 which, when rings 30 are in position on pipes 10 and 11, engage diametrically disposed radial lugs 35 projecting outwardly from the ends of casting 12. The ends of rings 30 are bent outwardly to form ears 30^a and seated in these ears are bolts 36 having nuts 37.

In assembling the muffler cut-out in position, a short section of the exhaust pipe is cut away, leaving ends 10 and 11. Clamping rings 30 are then threaded on each end 10 and 11 and casting 12 is then positioned on pipe 10 a sufficient distance to permit the insertion of end 11 into the opposite end of casting 12, after which casting 12 is moved forward on pipe 11 until the end of pipe 11 engages lug 20 formed on one of the inner annular flanges 12^a. Rings 30 are moved toward the ends of casting 12 so that slots 34 engage lugs 35, and flanges 31 close the ends of casting 12. Rings 30 are now clamped in position on pipes 10 and 11 by tightening nuts 37 on bolts 36. Packing 19, which has been tamped into the annular chambers 12^b after casting 12 has been properly positioned on pipes 10 and 11 and before links 30 were clamped on said pipes, forms an air-tight joint and prevents the escape of gases from the exhaust pipe.

Normally, valve 18 is seated on annular flange 17 by spring 26 engaging arm 22. When arm 27 is operated, arm 22 is rocked, causing its valve carrying end to move inwardly and upwardly, thereby seating valve 18 against seat 14^a and connecting chamber 15 with the atmosphere through opening 16. Housing 21 encloses the outer end of arm 22 and prevents carbon and dust from collecting in bearings 22^a. Valve 18 can be placed in chamber 15 in any suitable manner, preferably by embedding said valve in the sand core which is used in the manufacture of casting 12.

In the modified form shown in Figure 6, one leg 39 of the slotted lug 40 is extended as shown in dotted lines, so that the end of said leg can be bent and folded against the short leg 41, as shown in full lines, thereby closing the open end of slot 34 and retaining lugs 35 in position in slots 34. By clos-

ing the slots 34, rings 30 are positively locked to casting 12. To remove ring 30, the bent ends of legs 39 can be straightened so as to permit the withdrawal of lugs 35 from slots 34.

A muffler cut-out of my improved construction is simple and durable, requires few parts, will positively seal the exhaust chambers to the atmosphere, and is inexpensive to manufacture.

Obviously, various changes and arrangement of parts can be made and substituted for those herein shown and described, without departing from the spirit of my invention, the scope of which is set forth in the appended claims.

What I claim is:

1. In a muffler cut-out, a single piece casting adapted to be interposed in the exhaust pipe of an engine, said casting being provided with a transverse valve seat adjacent to its muffler end and having a discharge opening formed in its wall, there being an inwardly presented annular flange formed in said casting and encircling said opening, a valve adapted to be seated on said flange for closing said opening, an arm pivotally mounted on the exterior of said casting and having its free end projecting thereinto through said opening, flexible operative connection between said valve and said free end of said arm, resilient means for holding said valve on said annular flange, means for actuating said arm and moving said valve into engagement with said transverse seat, and means adapted to be secured to said exhaust pipe adjacent to each end of said casting for holding the latter against longitudinal and rotative movements.

2. In a muffler cut-out, a tubular one piece casting adapted to be interposed in the exhaust pipe of an engine, said casting having a valve seat formed transversely within said casting and adjacent to the muffler end thereof, and a discharge opening formed substantially parallel with the longitudinal axis of said casting, an inwardly presented annular flange formed on the lower face of said casting and surrounding said discharge opening, a valve seated on said flange and adapted to close said opening, a marginal flange depending from said valve and enclosing the upper portion of said annular flange, a housing formed integral with and projecting outwardly from said valve, a pin transversely mounted in said housing and having its ends fixed in the side walls thereof, lugs projecting outwardly from the underside of said casting, a shaft journaled in said lugs, an arm one end of which is fixed to said rod and whose opposite end extends into said housing and is provided with convex side faces which bear against the side walls of said housing and a knife edged bearing in which said transverse pin is

seated, and means for actuating said shaft whereby said arm is moved inwardly into said casting through said discharge opening and seats said valve in said transverse seat.

- 5 3. In a muffler cut-out, a one piece tubular casting adapted to be interposed in the exhaust pipe of an engine and provided at its ends with annular chambers which are designed to receive packing, an inwardly presented annular flange formed on the lower face of said casting and surrounding a discharge opening formed in said casting, a valve seated on said flange and adapted to close said discharge opening, said valve having a marginal flange presented outwardly and downwardly of said annular flange, a housing formed integral with and depending from said valve, a horizontally disposed pin fixed in said housing, a shaft journaled in bearings formed on the exterior of said casting, an arm fixed to said shaft and having its free end extended within said housing and provided with a bearing for said pin whereby said valve is pivotally supported on said arm and permitted to rock so that it can align itself with its seat, yielding means for holding said valve seated on said annular flange thereby closing said discharge opening, and means for operating said shaft to move said valve from its seat into a position within said casting whereby the communication between the exhaust pipe and the muffler end of the casting is blocked.
4. In a muffler cut-out, a one piece tubular casting adapted to be interposed in the exhaust pipe of an engine and provided at its ends with annular chambers which are designed to receive packing, an inwardly presented annular flange formed on the lower face of said casting and surrounding the discharge opening formed in said casting, a valve seated on said flange and adapted to close said discharge opening, said valve having a marginal flange presented outwardly and downwardly of said annular flange, a housing formed integral with and depending from said valve, a horizontally disposed pin fixed in said housing, a shaft journaled in bearings formed on the exterior of said casting, an arm fixed to said shaft and having its free end extended within said housing and provided with a knife edge bearing for said pin whereby said valve is pivotally supported on said arm and adapted to receive a rocking movement so that it can align
- itself with its seat, yielding means for holding said valve seated on said annular flange thereby closing said discharge opening, means for operating said shaft and moving said valve from its seat into a position within said casting whereby communication between the exhaust pipe and the muffler end of said casting is blocked, and split rings adapted to be clamped on said exhaust pipe to hold said casting against longitudinal and rotative movements.
5. In a muffler cut-out, a one piece tubular casting adapted to be interposed in the exhaust pipe of an engine and provided at its ends with annular chambers which are designed to receive packing, an inwardly presented annular flange formed on the lower face of said casting and surrounding a discharge opening formed on said casting, a valve seated on said flange and adapted to close said discharge opening, said valve having a marginal flange presented outwardly and downwardly of said annular flange, a housing formed integral with and depending from said valve, a horizontally disposed pin fixed in said housing, a shaft journaled in bearings formed on the exterior of said casting, an arm fixed to said shaft and having its free end extended within said housing to form a rocking bearing for said pin so that said valve can align itself with its seat, yielding means for holding said valve seated on said annular flange thereby closing said discharge opening, means for operating said shaft to move said valve from its seat into a position within said casting whereby communication between the exhaust pipe and the muffler end of said casting is blocked, split rings adapted to be clamped on said exhaust pipe and having an outwardly presented annular flange which is arranged to abut the ends of said casting and close the packing spaces formed therein, longitudinal inwardly presented lugs formed on said flange and provided with open slots, and lugs formed integral with the ends of said casting and projecting radially therefrom and adapted to be engaged by slots in said lugs when said rings are clamped in position on said exhaust pipe.

In testimony whereof I hereunto affix my signature this 28th day of March, 1921.

RICHARD SCHEID.
